UNITED STATES PATENT OFFICE.

LEE H. PARKER, OF BOSTON, MASSACHUSETTS, ASSIGNOR TO SPRAY ENGINEERING COMPANY, OF BOSTON, MASSACHUSETTS, A CORPORATION OF MASSACHUSETTS.

SPRAY-NOZZLE.

1,309,596.

Specification of Letters Patent.

Patented July 8, 1919.

Application filed December 1, 1917. Serial No. 204,962.

To all whom it may concern:

Be it known that I, LEE H. PARKER, a citizen of the United States, and a resident of Boston, in the county of Suffolk and State of Massachusetts, have invented an Improvement in Spray-Nozzles, of which the following description, in connection with the accompanying drawings, is a specification, like characters on the drawings representing like parts.

This invention relates to spray nozzles of general application, but more particularly intended for distributing liquids or liquids containing more or less solid matter.

While my invention is not restricted to such use, an important object thereof is to provide a nozzle for cooling water in or in connection with cooling ponds, or for condensers, ice plants, mills or any industry requiring a supply of cooling water or liquid.

By the nozzle herein disclosed I form and distribute over preferably an extended area a spray composed of or comprising water or other liquid or suitable fluid, and in accordance with the disclosed and preferred embodiment of my invention I discharge the liquid in a spray that is of substantially uniform homogeneity throughout. Such a spray may be used in any of the defined relations or for any other suitable purpose, as, for example, for spraying effluent, for precipitating or for spraying coal dust or other foreign matter, for air washing, for condensing vapors, for humidifying air and for other purposes.

In carrying out my invention, I project the fluid in a flaring spray, and within the nozzle I preferably simultaneously produce an inner jet which in this embodiment of my invention is a substantially central or axial jet and one or more surrounding jets which are preferably and for best results mixed within the mixing chamber of the nozzle, so that there is an effective mixture or blending of the jets before they issue in spray form from the mixing chamber, which latter is preferably so shaped as or is provided with means to cause impact and mixing of the several jets within the confined space of the mixing chamber of the nozzle.

In order that the principle of the invention may be readily understood, I have in

the accompanying drawing disclosed a single type of nozzle embodying my invention and wherein—

Figure 1 is a side elevation of such nozzle; Fig. 2 is a vertical section thereof; Fig. 3 is a plan view thereof; Fig. 4 is a plan view thereof with the cap removed; and

Figs. 5, 6 and 7 are respectively a vertical section and transverse sections on lines 6—6 and 7—7 of Fig. 5 of a slightly modified form of my invention.

Referring more particularly to the drawing the nozzle herein shown comprises a shell or casing 1, the lower end of which is adapted to be attached to a hose or pipe for conveying the water or other liquid. To that end, I have herein represented said shell or casing 1 as threaded at its lower end 2. Preferably also the upper end of the shell or casing 1 is threaded as represented at 3 for the reception of the head or cap 4 of the nozzle which is interiorly threaded. My invention is, however, not limited to a nozzle wherein the parts 1 and 4 are separate or detachable, since they might be formed in a single piece. Preferably for convenience in manufacture the members 1 and 4 are detachable.

The head or cap 4 is provided with a suitable discharge orifice 5 herein represented as circular. The interior of the head or cap 4 constitutes a mixing chamber, and it is preferably tapering or more or less dome shaped, so that the streams of liquid are caused to mix and intermingle prior to their discharge through the outlet 5.

In the patent to Eneas, No. 1,101,264, dated June 23, 1914, there is disclosed a spray nozzle having a central axially arranged sleeve or tube through which the central or axial jet passes, surrounding spiral vanes being provided to convey a plurality of streams of liquid in spiral directions, all the streams being caused to meet and intermingle within the mixing chamber.

It is the purpose of my invention to provide an inner jet which in the disclosed embodiment of my invention (to which, however, I am not limited) is a central or substantially axial jet, and one or more surrounding preferably spiral jets, although

within the broad scope and purpose of my invention, the surrounding jet or jets may be of any suitable character. I shall in the ensuing description refer to that embodiment of my invention wherein I have illustrated for purposes of disclosure the preferred embodiment, the inner jet as substantially central or axial. Preferably the surrounding jets are formed by reason of the provision of spirals which may be of any suitable character, but instead of providing a central tube or sleeve for the central or substantially axial jet, I omit the physical tube or sleeve or other element defining the circumferential boundary of the central or axial jet. I, however, obtain the inner or central or substantially axial stream or jet by positioning or forming the vanes or spirals or other elements by which the surrounding jet or jets are formed in such manner as to permit the passage of the inner or central jet. In the disclosed embodiment of my invention I have accomplished this result by inwardly terminating the vane or vanes at a suitable distance radially from the axis of the nozzle so as to leave an unobstructed axial passage through which the liquid passes in a straight stream. Still I may, however, form or shape or position said vane or vanes in any way permitting the liquid to issue axially or substantially centrally between them or within the convolutions of the vane if a single one only be employed.

In accomplishing the result in this particular form of my invention, I provide a plurality of spirals 6 of any suitable pitch and of any suitable radial extent. I have herein represented said spirals as cast or otherwise formed with the shell or casing 1, but within the scope and purpose of my invention, they may be separately formed and attached thereto in any suitable manner, or positioned frictionally or otherwise within the nozzle. Preferably the said spirals terminate at or below the upper end of the shell or casing 1, that is, at or below the base of the mixing chamber, so that the liquid is discharged from the upper end of the spirals directly against the inner wall 7 of the mixing chamber and in such manner that the stream or streams which are outwardly thrown under centrifugal force, are guided by the inner surface 7 across the discharge opening 5 where or below which they meet the inner, and herein the central jet herein indicated at 8, with the result that all the jets are thoroughly mixed and intermingled within the mixing chamber 8', and so that they issue therefrom in a flaring spray of substantially uniform homogeneity in cross section.

Preferably each of the spirals 6 at its lower end merges into the inner surface 9 of the shell or casing 1 as indicated at

10, and at the upper end each of said spirals again merges into the inner wall of the shell or casing as indicated at 11, thus presenting as little obstruction as possible to the spiral streams, particularly at the lower end thereof. In other words, the spiral or spirals 6 taper toward or are of gradually decreasing width at the points where they merge into the inner surface of the shell 9. Within the broad scope and purpose of my invention, however, they may be of full width at both their upper and their lower ends, or of any suitable intermediate widths.

Since, however, an important but by no means an exclusive use of my invention is the spraying of sewage, which contains more or less solid matter, I preferably so construct the spiral or spirals that they present the least resistance to the flow of the material, while preserving the flow of the material in an inner and herein a central jet, and in one or more outer jets which preferably are spiral. Preferably and in the disclosed embodiment of the invention, the diameter of the inner or substantially central opening is at least substantially one-third the diameter of said vane or vanes and is substantially equal to the full diameter of the outlet from the nozzle, thus permitting the ready use of the nozzle with a liquid containing solid matter, such as sewage.

In order further to decrease the obstruction presented by the spiral or spirals, the inner edge 12 thereof is made rounding in cross section, as clearly indicated in Fig. 2.

Preferably each of the vanes is made of a decreasing pitch, so that the surrounding jet or jets are brought gradually from the flow in the direction of the entering stream 109 to a flow in a direction at approximately right angles to the stream flow and approximately tangential thereto. Thus, the surrounding jet or jets are, with the least possible obstruction, brought into a direction 110 of flow so as thoroughly to mix and intermingle with the inner and herein the central jet.

The inner and herein the central jet is preferably a straight one though within the scope and purpose of my invention, it may be rotatory in whole or in part. The cylindrical surface of such inner and herein central jet may have more or less of a rotatory motion, which may be caused in part by the effect of the surrounding jet or jets, which are not separated from the inner and herein central jet by a physical wall.

The outer or surrounding jet or jets partake of their described paths, partly through centrifugal action, but the inner and herein central jet is not under the influence of centrifugal action and maintains a substantially straight course into the mixing chamber 8.

In the said mixing chamber the inner and herein central jet meets the surrounding jet or jets and thus the liquid or fluid of the jets is mixed and blended within a confined 5 chamber or space. The mixed mass issues from the chamber in a spray which is of substantially uniform homogeneity throughout.

While the several jets or streams are 10 mixed within the mixing chamber 8', substantially as set forth in the said patent to Eneas, No. 1,101,264, I have found in practice that the described provision of means for effecting the formation of an inner and 15 herein a central jet and one or more surrounding jets peculiarly co-operates with the mixing chamber and particularly in that the liquid from all the jets enters with a minimum of obstruction into the mixing chamber 20 and in streams of such unimpeded force as to result in an even more effective mixing than heretofore. Moreover, I find that in some cases there is or may be a preliminary mixing at the very base of the mixing 25 chamber, that is, at the point where the several streams enter thereinto. This is owing to the fact that no physical wall is present, so as accurately or exactly to define the shape or radial extent of the inner and 30 herein central jet or stream.

Within the scope and purpose of my invention, the mixing chamber need not be employed, although it preferably and for best results is employed, since so far as I 35 am aware I am the first to effect the formation of an inner and herein a central jet and one or more surrounding jets in substantially the manner herein described.

As hereinbefore stated, the surrounding or 40 outer jet or jets may be of any suitable character. While therefore I preferably use a spiral vane or vanes therefor, it is clear that the vane or vanes need not be of a spiral character so long as it or they are substantially a surrounding or outer vane or vanes, 45 so as to produce an outer or surrounding jet or jets.

Within the scope and purpose of the invention, the so-called central or axial jet 50 need not be wholly axial or throughout the entire extent thereof and particularly at its lower end. The vane or vanes 6 may be so shaped that only throughout a portion of the length thereof does the water pass 55 through axially, thus forming the central jet. The remainder of the length of the passage or space wherethrough passes the water that ultimately forms the central or axial jet may be somewhat spiral or not 60 truly axial, so that as to a portion at least of the course of the liquid that ultimately becomes the central or actual jet or stream, there may be somewhat of a whirling action. Throughout the upper portion, however, of 65 the course of the liquid that becomes the cen-

tral jet, the liquid in the disclosed embodiment of the invention has a substantially truly axial or central location or relation with respect to the shell or casing 1.

Thus, while for best results I prefer to 70 have the central or axial jet truly central or axial throughout its entire extent and throughout substantially the entire length of the shell or casing 1, I may (referring to the disclosed embodiment of the invention) 75 so construct the nozzle that the liquid does not immediately, where it enters the nozzle, partake of such central stream character, provided it does so before the mixing chamber is reached. In other words the liquid 80 entering the nozzle might all come under the influence preliminarily of the vane or vanes, which are however so formed at their upper portions as to result in the formation of the said central jet or stream. 85 This depends upon the shape and position of the inner edge of the vane or vanes. If a central plug or obstruction be provided at the base of the vane or vanes, this is within the scope of my invention, since such 90 plug or obstruction, if present, is of restricted length, and the liquid immediately thereabove partakes of the said central-stream character. This form of my invention is represented in Figs. 5, 6 and 7, where- 95 in the central or axial obstruction is represented at 13, and the opening which is at one side thereof is represented at 14. It is here shown as of substantially the same diameter as in Fig. 2.

For the best results, and particularly where the nozzle is used in the spraying of sewage, or in the spraying of liquid containing more or less solid matter (to which use, however, my invention is in no wise limited), 100 the central passage is of approximately one third of the diameter of the entire passage through the nozzle and is approximately the diameter of the outlet from the nozzle.

Having thus described one illustrative 110 form of my invention, I desire it to be understood that although specific terms are employed, they are used in a generic and descriptive sense and not for purposes of limitation, the scope of the invention being 115 set forth in the following claims.

1. A spray nozzle comprising a shell or casing having an inlet and an outlet and also having one or more spirally arranged vanes between said inlet and outlet for directing the liquid in a spiral jet or jets, said vane or vanes having at least a portion of the inner edge thereof radially spaced from the axial center of the nozzle sufficiently to leave an opening for the passage of a central 120 jet of liquid in contact with such portion of said inner edge or edges, the inner surface of the shell or casing in proximity to the outlet tapering inward to a markedly 125 greater extent than the preceding part of 130

- the said surface, thereby to direct the spiral jet or jets in a marked change in direction into an intensified or increasing mixture with the particles of the central jet at a zone 5 in proximity to the outlet.
2. A spray nozzle comprising a shell or casing having an inlet and an outlet and also having one or more spirally arranged vanes between said inlet and outlet for directing the liquid in a spiral jet or jets, said 10 vane or vanes at the end thereof nearest the outlet having the inner edge or edges thereof radially spaced from the axial center of the nozzle sufficiently to leave an opening 15 for the passage of a central jet of liquid in contact with the said edge of said vane or vanes, the inner surface of the shell or casing in proximity to the outlet tapering inward to a markedly greater extent than the 20 preceding part of the said surface, thereby to direct the spiral jet or jets in a marked change in direction into an intensified or increasing mixture with the particles of the central jet at a zone in proximity to the 25 outlet.
3. A spray nozzle comprising a shell or casing having an inlet and an outlet and also having one or more spirally arranged vanes between said inlet and outlet for directing the liquid in a spiral jet or jets, said 30 vane or vanes having a portion at least of the inner edge thereof radially spaced from the axial center of the nozzle, thereby to leave an opening for the passage of a central jet of liquid in contact with such portion 35 of said inner edge or edges, and a mixing chamber in advance of said vane or vanes into which said central and said surrounding jet or jets are discharged and wherein they are thoroughly mixed before 40 issuing from said outlet, the inner surface of the wall of said mixing chamber in proximity to the outlet tapering inwardly to a markedly greater extent than the preceding 45 part of said surface, thereby to direct the spiral jet or jets in a marked change in direction into an increasing mixture with the particles of the central jet at a point in proximity to the said outlet.
4. A spray nozzle comprising a shell or casing having an inlet and an outlet and also having one or more spirally arranged vanes between said inlet and outlet for directing the liquid in a spiral jet or jets, said 55 vane or vanes having a portion at least of the inner edge thereof radially spaced from the axial center of the nozzle, thereby to leave an opening for the passage of a central jet of liquid in contact with such portion of 60 said inner edge or edges, and co-acting means for effecting the intermixing of all the jets and the issuance thereof from said outlet in a spray of substantially uniform homogeneity, said means including a mixing chamber within said shell or casing, the 65 inner surface 7 of the wall thereof in proximity to the outlet being tapered markedly inward in comparison with the preceding portion of the surface of said wall.
5. A spray nozzle comprising a shell or 70 casing having an inlet and an outlet and also having one or more spirally arranged vanes between said inlet and outlet for directing the liquid in a spiral jet or jets, said vane or vanes at the end thereof nearest the outlet having the inner edge or edges thereof radially spaced from the axial center of the nozzle sufficiently to leave an opening for the passage of a central jet of liquid in contact with the said edge of the said vane or 75 vanes, the inner edges of said vanes at the end thereof nearest the inlet being of gradually increasing radial extent in the direction of the flow of liquid, thereby to lessen the obstruction presented by said vane or vanes 80 to the flow of the liquid.
6. A spray nozzle comprising a shell or casing having one or more spirally arranged vanes between said inlet and outlet for directing the liquid in a spiral jet or jets, said 85 vane or vanes having the inner edge or edges thereof at the end nearest the outlet radially spaced from the axial center of the nozzle sufficiently to leave an opening for the passage of a central jet of liquid in contact with the said edge of the said vane or vanes, the inner edges of said vane or vanes at both ends thereof tapering toward and merging into the inner surface of the shell or 90 casing.
7. A spray nozzle comprising a shell or 95 casing having an inlet and an outlet and also having one or more spirally arranged vanes between said inlet and outlet for directing the liquid in a spiral jet or jets, the inner edges of said vane or vanes being shaped and positioned to permit and effect the formation and passage of a substantially central or axial jet that is without a physical wall separating it from the outer 100 spiral jet or jets, whereby a preliminary meeting or partial mixing of the liquid of the several jets may occur at the exit end of said vane or vanes the inner surface of the shell or casing in proximity to the outlet 105 tapering inward to a markedly greater extent than the preceding part of the said surface, thereby to direct the spiral jet or jets in a marked change in direction into an intensified or increasing mixture with the particles of the central jet at a point in proximity to the outlet.
8. A spray nozzle comprising a shell or 110 casing having an inlet and an outlet and also having one or more spirally arranged 115 vanes between said inlet and outlet for directing the liquid in a spiral jet or jets, and a mixing chamber in advance of the said vanes and between the same and said outlet having the portion of the inner surface 120

- 7 of the wall thereof tapered inwardly in proximity to the outlet markedly in comparison with the preceding portion of said surface, said vane or vanes having the inner 5 edges thereof nearest the mixing chamber sufficiently radially removed from the axial center of the nozzle to leave an opening for the passage of a central jet of liquid in contact with the said inner edge of said 10 vane or vanes, whereby a preliminary contact or partial intermixing of said central and surrounding jet or jets may occur within the base of the mixing chamber followed by a complete intermixing of said jets with 15 in said chamber in proximity to said outlet and before issuance from the said outlet.
9. A spray nozzle comprising a shell casing having an inlet and an outlet and also having one or more spirally arranged vanes 20 between said inlet and outlet for directing the liquid in spiral jet or jets, said vane or vanes having the inner edge thereof radially spaced from the axial center of the nozzle, thereby to leave an opening for the passage 25 of a central jet of liquid in contact with said inner edge or edges, said vane or vanes being of decreasing pitch in the direction of the flow of liquid, thereby gradually to change the direction of flow of the liquid 30 and to reduce to a minimum the friction thereof in its passage through the nozzle.
10. A spray nozzle comprising a shell or casing having an inlet and an outlet and also having one or more spirally arranged 35 vanes between said inlet and outlet for directing the liquid in a spiral jet or jets, said vane or vanes having the inner edge thereof radially spaced from the axial center of the nozzle, thereby to leave an opening for 40 the passage of a central jet of liquid in contact with such portion of said inner edge or edges, and a mixing chamber in advance of said vane or vanes, the inner surface of said mixing chamber being so shaped and 45 the vane or vanes being of decreasing pitch in the direction of flow of the liquid, whereby in coöperation with the inner surface of the mixing chamber the surrounding jet or jets are gradually brought from a flow in 50 the direction of the entering stream to a flow at approximately right angles thereto and crossing the outlet where they encounter the central jet and are thoroughly mixed thereby within the mixing chamber.
- 55 11. A spraying nozzle comprising a shell or casing having an inlet and an outlet and also having one or more spirally arranged vanes between said inlet and outlet for directing the liquid in a spiral jet or jets, said vane or vanes having the inner edge thereof radially spaced from the axial center of the nozzle, thereby to leave an opening for the passage of a central jet of liquid in contact with such portion of said inner 60 edge or edges, and a mixing chamber in 65
- advance of said vane or vanes, the inner surface of said mixing chamber being so shaped that the surrounding jet or jets are brought from a flow in the direction of the entering stream to a flow at approximately right 70 angles thereto, and crossing the outlet where they encounter the central jet and are thoroughly mixed thereby within the mixing chamber.
12. A spraying nozzle comprising a shell 75 or casing having means to produce a central jet and one or more surrounding jets, and a mixing chamber in advance of the means for producing said jets, said mixing chamber having an outlet, and the inner surface 80 of the wall of said chamber in proximity to said outlet being markedly tapering in comparison with the preceding part of said wall, and so shaped as to direct said surrounding jet or jets in a direction which 85 approximates a right angle to the direction of the inflow of the stream through the nozzle, whereby an intensified mixing action is effected in proximity to the said outlet.
13. A spraying nozzle comprising a shell 90 or casing having means to produce a central jet and one or more surrounding jets, and a mixing chamber in advance of the means for producing said jets, said mixing chamber having an outlet, and the inner 95 surface of the wall of said chamber in proximity to said outlet being of a flattened dome shape and extending from a preceding substantially cylindrical portion of said mixing chamber whereby said surrounding jet or 100 jets are guided by said inner surface of the wall in a direction which approximates a right-angle to the direction of the inflow of the stream through the nozzle, and into thorough intermixing relation with the central 105 jet.
14. A spraying nozzle comprising a shell or casing having an inlet and an outlet and also having one or more spirally arranged vanes 110 between said inlet and outlet for directing the liquid in a spiral jet or jets, the inner edges of said vane or vanes being shaped and positioned to permit and effect the formation and passage of a substantially central or axial jet that is without a physical 115 wall separating it from the outer spiral jet or jets, whereby a preliminary meeting or partial mixing of the liquid of the several jets may occur at the exit end of said vane or vanes, and a mixing chamber in advance 120 of the said vanes, said mixing chamber having at its outlet the outlet for said shell or casing, and the inner surface of the wall of the mixing chamber in proximity to said outlet being of a flattened, dome shape and 125 extending from a preceding, substantially cylindrical portion of said mixing chamber, whereby said surrounding jet or jets are guided by said inner surface of the wall in a direction which approximates a right an- 130

gle to the direction of the inflow of the stream through the nozzle and into thorough intermixing relation with the central jet.

15. A spray nozzle comprising a shell or casing having an inlet and an outlet and also having one or more spirally arranged vanes between said inlet and outlet for directing the liquid in a spiral jet or jets, the inner edges of said vane or vanes being shaped and positioned to permit and effect 5 the formation and passage of a substantially central or axial jet that is without a physical wall separating it from the outer spiral jet or jets, whereby a preliminary meeting or 10 partial mixing of the liquid of the several jets may occur at the exit end of said vane or vanes, said vane or vanes being of decreasing pitch in the direction of flow of liquid, thereby gradually to change the 15 direction of flow of the liquid and to reduce to a minimum the friction thereof in its passage through the nozzle, and a mixing chamber in advance of the 20 said vanes, said mixing chamber having as its outlet the outlet for said shell or casing, and the inner surface of the wall of the mixing chamber in proximity to said outlet being of a flattened, dome shape and extending 25 from a preceding, substantially cylindrical portion of said mixing chamber, whereby 30 said surrounding jet or jets are guided by said inner surface of the wall in a direction which approximates a right angle to the direction of the inflow of the stream through 35 the nozzle and into thorough intermixing relation with the central jet.

16. A spray nozzle comprising a shell or casing having an inlet and an outlet and also having one or more spirally arranged 40 vanes between said inlet and outlet for directing the liquid in a spiral jet or jets, the inner edges of said vane or vanes being shaped and positioned to permit and effect 45 the formation and passage of a substantially central or inner jet that is without a physical wall separating it from the outer spiral jet or jets, whereby a preliminary meeting or 50 partial mixing of the liquid of the several jets may occur at the exit end of said vane or vanes, the diameter of said substantially central or inner jet being at least one-third the diameter of the whole passage through the nozzle, thus permitting the 55 ready use of the nozzle with liquid containing solid matter.

17. A spray nozzle comprising a shell or casing having an inlet and outlet and also having one or more spirally arranged vanes between said inlet and outlet for directing 60 the liquid in a spiral jet or jets, the inner edges of said vane or vanes being shaped and positioned to permit and effect the formation and 65 passage of a substantially central or inner jet that is without a physical wall separating it from the outer spiral jet or jets,

whereby a preliminary meeting or partial mixing of the liquid of the several jets may occur at the exit end of said vane or vanes, the diameter of said substantially central or inner jet being at least one-third the diameter of the whole passage through the nozzle, thus permitting the ready use of the nozzle with liquid containing solid matter, the inner surface of the shell or casing in proximity to the outlet tapering inward to a 70 markedly greater extent than the preceding part of the said surface, thereby to direct the spiral jet or jets in a marked change in direction into an intensified or increasing mixture with the particles of the central 75 jet as a zone in proximity to the said outlet.

18. A spray nozzle comprising a shell or casing having an inlet and outlet and also having one or more spirally arranged vanes between said inlet and outlet for directing 80 the liquid in a spiral jet or jets, the inner edges of said vane or vanes being shaped and positioned to permit and effect the formation and passage of a substantially central or axial jet that is without a physical 85 wall separating it from the outer spiral jet or jets, whereby a preliminary meeting or partial mixing of the liquid of the several 90 jets may occur at the exit end of said vane or vanes, the substantially central or axial jet being of approximately the full diameter of the outlet from said nozzle, and the inner surface of the shell or casing in proximity to the outlet tapering inward to a 95 markedly greater extent than the preceding 100 part of the said surface, thereby to direct the spiral jet or jets in a marked change in direction into an intensified or increasing mixture with the particles of the central jet at a zone in proximity to the said outlet.

19. A spray nozzle comprising a shell or casing having an inlet and an outlet and also having one or more spirally arranged vanes between said inlet and outlet for directing the liquid in a spiral jet or jets, the inner edges of said vane or vanes being shaped and positioned to permit and effect 110 the formation and passage of a substantially central or inner jet that is without a physical wall separating it from the outer spiral jet or jets, the diameter of said central jet being at least substantially one-third the diameter of said vane or vanes, thus permitting the ready use of the nozzle with liquid containing solid matter, said shell or 115 casing having a mixing chamber between the outlet and said vanes.

20. A spray nozzle comprising a shell or casing having an outlet and an inlet and also having one or more inclined vanes between said inlet and outlet for directing the liquid in an inclined outer jet or jets, the inner edges of said vane or vanes being shaped and positioned to permit and effect 120 the formation and passage of a substantially 125 inclined inner jet or jets,

central or inner jet that is without a physical wall separating it from the outer inclined jet or jets, the diameter of said central jet being at least substantially the full diameter of said outlet and also of sufficient cross sectional area to permit the ready use of the nozzle with liquid containing solid matter, said shell or casing having a mixing chamber between the outlet and said vane or vanes.

21. A spray nozzle comprising a shell or casing having an inlet and an outlet and also having one or more spirally arranged vanes between said inlet and outlet for directing the liquid in a spiral jet or jets, the inner edges of said vane or vanes being shaped and positioned to permit and effect the formation and passage of a substantially central or inner jet that is without a physical wall separating it from the outer spiral jet or jets, the diameter of said central jet being at least substantially one-third the diameter of said vane or vanes and equal to the full diameter of said outlet, thus permitting the ready use of the nozzle with a liquid containing solid matter, said shell or casing having a mixing chamber between the outlet and said vane or vanes.

22. A spray nozzle comprising a shell or casing having an inlet and an outlet, and also having one or more inclined vanes between said inlet and outlet for directing the liquid in an inclined outer jet or jets, the inner portion of said vane or vanes being shaped and positioned to permit and effect the formation and passage of an inner jet that is without a physical wall separating it from the said inclined jet or jets, the diameter of said inner jet being at least one-third the diameter of said vane or vanes.

23. A spray nozzle comprising a shell or casing having an inlet and an outlet, and also having one or more inclined vanes be-

tween said inlet and outlet for directing the liquid in an inclined, outer jet or jets, the inner portion of said vane or vanes being shaped and positioned to permit and effect the formation and passage of an inner jet that is without a physical wall separating it from the said inclined jet or jets, the diameter of said inner jet being at least substantially one-third the diameter of said vane or vanes and said shell or casing having a mixing chamber between the outlet and said vane or vanes.

24. A spray nozzle comprising a shell or casing having an inlet and an outlet and also having one or more inclined vanes between said inlet and outlet for directing the liquid in an inclined, outer jet or jets, the inner portion of said vane or vanes being shaped and positioned to permit and effect the formation and passage of an inner jet that is without a physical wall separating it from the said inclined jet or jets, the diameter of the inner jet being at least one-third the diameter of the entire passage through the nozzle and also approximately the diameter of the outlet from the nozzle.

25. A spray nozzle comprising a shell or casing having an inlet and an outlet and also having one or more inclined vanes between said inlet and outlet for directing the liquid in an inclined jet or jets, the inner portion of said vane or vanes being shaped and positioned to permit and effect the formation and passage of an inner jet that is without a physical wall separating it from the said inclined jet or jets, the diameter of the inner jet being at least substantially the full diameter of the outlet from the nozzle and at least one-third the diameter of the entire passage through the nozzle.

In testimony whereof I have signed my name to this specification.

LEE H. PARKER.
